UNITED STATES PATENT OFFICE.

GOTTLIEB HOERSCH, OF PHILADELPHIA, PENNSYLVANIA.

REVERSIBLE WINDOW-SASH.

SPECIFICATION forming part of Letters Patent No. 673,655, dated May 7, 1901.

Application filed July 17, 1900. Serial No. 23,892. (No model.)

To all whom it may concern:

Be it known that I, GOTTLIEB HOERSCH, a citizen of the United States, residing at Philadelphia, in the county of Philadelphia, in the 5 State of Pennsylvania, have invented a new and useful Improvement in Reversible Window-Sashes, of which the following is a specification.

My invention relates to improvements in 10 sashes which are adapted to be raised and lowered as usual and are hinged, so that they may be swung into an apartment or reversed, whereby their outer sides are accessible for washing, glazing, repairs, or other purposes.

15 The invention consists of novel features, as will be hereinafter described, and pointed out in the claims.

Figure 1 represents a partial front view and a partial vertical section of reversible window-sashes embodying my invention. Fig. 2 represents a horizontal section thereof, the sashes being shown as swung into the apartment. Fig. 3 represents a view of a portion of the inner side of the window-frame and adjacent stiles of the sashes. Fig. 4 represents a horizontal section of a portion on line $x-x$, Fig. 1. Fig. 5 represents a vertical section of a portion on line $y-y$, Fig. 4. Figs. 6 and 7 represent perspective views of supplementary coupling mechanism employed.

Similar letters of reference indicate corresponding parts in the figures.

Referring to the drawings, A designates a window-frame, and B and C the upper and 35 lower sashes thereof. The sash B has its side stiles formed in sections C' D and E F, the sections C' D being connected by the hinges G, whereby the sash B may be turned inwardly on said hinges, as shown in Fig. 2, so 40 that the outer side of said sash is accessible for purposes of cleaning, glazing, repairs, &c., it being noticed that the cords H of said sash B are connected with the section C'. The sections E and F are adapted to be coupled or 45 connected by means of the bolt J on the section F, whereby they may be moved as one in the raising and lowering of the sash; but when the sash is to be turned on the hinges G the bolt is thrown in the present case to 50 the right, whereby it leaves the section E, and the sash is disconnected from the section F, and the latter retains its position during the

swinging in or out of the sash, it being noticed that the section F has the sash-cord J² connected with it. In order to easily operate 55 the bolt J, the same is formed with a rack K, with which meshes the pinion L, whose shaft M is mounted on the adjacent portions of the section F and is provided with a knob or handle end N for convenience of grasping and rotating said shaft, and consequently the pinion L, whereby the bolt J may receive motion to the right or left, as the case may be. The shaft M is jointed, as at P, whereby its outer portion may be lowered, as most clearly shown 60 in Fig. 1, the section F having a casing Q therein, whereby said portion of the shaft may be seated thereon and so be removed from the path of the stiles of the sash C in the raising and lowering of the latter. The 65 sash C has its side stiles formed in the sections R S and T U, the sections S and R being connected by the hinges V, whereby said sash C may be turned on said hinges in the same manner as the upper sash B 70 and for similar purposes. It will here be noticed that the section S has the sash-cord W connected with it and the section U has the sash-cord X connected with it. On the upper end of the section S is the tongue Y, 75 which is adapted to ride freely against the parting-strip Z of the frame A and guide said section S of the sash C in its up-and-down motions, and also prevent said section S from pressing or being pressed against 80 the adjacent portion of the sash-cord W, said tongue also abutting against the portion of the meeting-rail A' on said section 'C. The ends of the section S are rabbeted, as at 85 B', so that when the sashes are in normal condition said sections have their joints braced one against the other and in close contact. The sections T and U are adapted to be coupled by the bolt C², the same having the 90 rack D' thereon, which is engaged by the pinion E', whose shaft F' is mounted on the section U, it being noticed that the latter has a case or box G' let thereinto to receive the outer portion of said bolt C², and the section T has a box H' therein, while the side stile 95 of the window-frame A has a box J' therein, the several boxes G', H', and J' being in line with each other and in communication, whereby the bolt C² may be shot into the box H' or 100

the box J', as desired, it being evident that when the nose of the bolt occupies the box H' the sections T and U are coupled as ones and they may rise and fall with each other.

5 When, however, it is desired to open the sash C, the bolt is shot in the present case to the right and its nose enters the box J', thus coupling or connecting the section U with the window-frame and rendering said section im-
movable, whereby it is prevented from being thrown up by the action of the sash-weight connected therewith by the cord X. When the sash is returned to its closed position, the bolt is thrown to the left, whereby it leaves the box J' and enters the box H', thus coupling the sections T and U as one, when the sash C may be raised and lowered, as usual. The shaft F' of the pinion E' is formed in sections pivoted to each other, as at F², where-
20 by its outer portion may be lowered and folded into the casing K' in the section U out of the way, but is convenient of access when it is required to rotate the pinion E', in which case the shaft is raised and may be turned, thus rotating the pinion, and consequently the bolt C², to the right or left, as the case may be. It will be noticed that the sections M F', that carry the pinions L E', are journaled on the rear walls of the casings Q and K', re-
25 spectively, each casing being sufficiently de-
pressed to receive both the pinion and the hinged or folding portion of the shaft. When the sashes are in normal position, the lower sash has its bottom portion resting on the sill 30 of the window-frame, so as to be covered by the bead L', while the top of the upper sash is above the lower edge of the bead M' of the cap. (See dotted lines, Fig. 1.) When the lower sash is to be opened, it requires to be raised above the bead L', when it can be turned on its hinges, after which the upper sash is accessible, so that when it is lowered below the bead M' it can be turned on its 35 hinges, as will be apparent in Fig. 2.

40 45 In order to relieve the bolts of the weight of the sashes, which would prevent their easy operation, I employ the bars or plates N' P', which are secured to the side sections F and U, said plates having vertical slots Q' therein, with laterally-extending horizontal throats R' leading to said slots, (see Figs. 1, 6, and 50 7,) said throats also extending through the outer face of the side stile.

The sections E and T have tongues S' se-
55 cured thereto, the same being adapted to enter the throats R' while the sashes are closing and pass down the slots Q' and rest on the walls of the bases of said slots, said bases being below said throats, so that the weight 60 of the sashes are in a measure superimposed on said walls, thus relieving the bolts of such weight. The under sides of said walls and those of the tongues S' are inclined, forming locking-joints, which prevent disconnection

of the sections E F and T U. When, how- 65 ever, the sections are unlocked by the proper operation of the bolts, the sashes are raised, so that the tongues S' ride upwardly in the slots Q' until they reach the throats R', when the sashes are swung outwardly on their 70 hinges, the tongues then passing through the throats, so that the sashes are disconnected from the side sections F and U.

The interlocking of the sashes with the side sections may be readily accomplished by 75 partly closing the sashes, raising them to a proper height, pushing the tongues into the throats, and then lowering the sashes, when the latter will again be connected or coupled. Then the bolts are operated to lock the re- 80 spective parts, when the sashes and side sections may be moved as one.

Having thus described my invention, what I claim as new, and desire to secure by Letters Patent, is—

85

1. In a reversible window-sash having side stiles formed of divided members, a rack-bolt adapted to lock said members and to engage the side stile of a window-frame, a casing adapted to be secured to one of said members, a shaft formed in sections, and a pinion engaging said rack-bolt and being mounted on one of said sections, said sections being hinged together and the outer section thereof being adapted to be folded into the chamber of 95 said casing, the shaft-section which carries said pinion being journaled on a wall of said casing.

2. In a reversible sash having sectional side stiles, a face-plate connected with one section, 100 said plate being formed with a vertical slot, and a lateral throat above the base of said slot extending through the outer face of the side stile forming an inlet to said slot, and a tongue on the other section adapted to pass 105 through said throat as the sash is closing and be seated on said base, said tongue and said slot being adapted to form a locking-joint.

3. A reversible window-sash having a side stile formed of divided members, a rack- 110 bolt adapted to lock said members and to interlock with the side stile of the window-frame, a pinion mounted on one of the members of the divided side stile, and meshing with said rack-bolt, and an auxiliary locking 115 device for the side stile of the sash, consisting of a plate connected with one member and having a vertical slot, and a lateral throat above the base of said slot, said throat extending through the outer face of the side 120 stile, and a tongue on the outer section adapted to pass through said throat when the sash is closing and be seated on said base forming a locking-joint.
